BARTON H. JENKS, OF BRIDESBURG, PENNSYLVANIA.

Letters Patent No. 87,341, dated March 2, 1869.

IMPROVEMENT IN LOOMS.

The Schedule referred to in these Letters Patent and making part of the same.

To all whom it may concern:

Be it known that I, BARTON H. JENKS, of Bridesburg, in the county of Philadelphia, and State of Pennsylvania, have invented certain new and useful Improvements in the Harness-Movements of Looms; and I do hereby declare that the following is a full, clear, and exact description thereof, reference being had to the accompanying drawings, making a part of this specification, in which—

Figure 1, plate 1, is a section through the loom-frame, taken in the course indicated by red line *y y* in fig. 2.

Figure 2, plate 1, is a section taken through the loom, in the vertical plane indicated by red line *x x* in fig. 1.

Figure 3, plate 2, is a plan view of the loom.

Figure 4, plate 2, is a sectional view, in detail, of the upper portion of one of the standards which support the heddles.

Similar letters of reference indicate corresponding parts in the several figures.

One of the objects of my invention is to effect, directly, the drawing down or depression of heddle-frames, by means of oscillating drums, to which said frames are connected by means of straps, in such manner that when one or more heddles are raised, the other heddle or heddles, which are in connection therewith, will be depressed or moved in a direction opposite to the motion of the rising heddle or heddles, as will be hereinafter explained.

Another object of my invention is to arrange a part of the whole number of treadles used in the loom for moving the heddle-frames, on each side of the loom-frame, when the treadles thus arranged are connected to and operate directly upon the top rollers, from which the heddle-frames are suspended, said treadles being actuated by separately-movable cams upon the cam-shaft, as will be hereinafter described.

To enable others skilled in the art to understand my invention, I will describe its construction and operation.

In the accompanying drawings—

A represents the frame of the loom, which may be constructed in any suitable, well-known manner; and

B B represent standards, which are erected on both sides of the loom-frame, for sustaining the heddle-frames *C C C*, three of which frames are represented in the drawings.

The upper ends of the two standards *B B* are enlarged in a suitable manner, so as to form bearing-heads, *a a*, which are adapted for receiving the journals of rollers, *D D D*, and sustaining these rollers, one above another, in different vertical and horizontal planes, as clearly shown in figs. 2 and 4.

Each one of these rollers *D* has four flanged drums, *b b, c c*, keyed upon it, as shown in fig. 1.

The drums *b b* have straps, *b' b'*, attached to them,

by means of which a heddle-frame, *C*, is suspended by both ends.

The drums *c c* are connected, by means of straps, *c' c'*, and rods or wires, *d d*, to the free ends of the treadles *E E*, which latter are applied beneath, and at right angles to a transverse crank-shaft, *F*, as shown.

The straps *c' c'*, of all the drums *c c*, are passed around these drums, in opposite directions to the suspension-straps *b' b'* of the heddle-frames, so that, when the treadles are depressed, their respective rollers *D* will be turned so as to wind the straps *b' b'* upon the drums *b b*, in a direction which will raise the heddle-frames.

The lower ends of the heddle-frames are connected, by means of straps *e e*, to horizontal drums *G*, in such manner that these heddle-frames are held down in place, under proper tension, and caused to descend at proper times.

The straps *e* are attached, on opposite sides of the drums *G*, in such manner that while one or one set of heddles is elevated, they will cause said drum or drums to rotate in a direction which will cause a depression of the opposite heddle, or set of heddles, as the case may be.

This is effected, as shown in figs. 1 and 2, by applying the straps *e* to the drums *G*, so that, when one strap or set of straps is being unwound from them, the opposite strap, or set of straps, will be correspondingly wound from them.

The drums *G* have their end-bearings in arms *H H*, which are secured between transverse bars, *A' A'*, of the frame *A*, in a suitably-inclined position, to keep the heddle-frames from contact with each other at their lower ends.

It will be seen, from the above description, that the upper horizontal rollers *D D D* are arranged upon an inclined plane, in such manner that the heddle-frames hang free from each other; consequently these frames, and their appurtenances, will not be chafed or worn out by rubbing against each other; and, while this is the case, the arrangement of the said rollers *D D* will admit of the heddle-frames being hung very closely together.

It will also be seen, from the above description, that one set of the heddle-frames is drawn down by the operation of the treadles in raising another set.

I am aware that it is not new to hold heddle-frames between two sets of rollers, or sheaves, one set being arranged below these frames, and the other set being arranged above them, with flexible cords or strap-connections passing around said rollers, or sheaves, and attached to vibrating arms applied on the sides of the loom-frame.

My arrangement differs from that just referred to, in that the lower rollers or drums *G* are so connected to the heddle-frames, that the descent of these frames is effected through the medium of the upper rollers *D*,

acted upon by the treadles, the drums being oscillated by the operation of the heddle-frames upon them, as described.

I also am aware that an auxiliary pulley and strap have been used, in connection with upper and lower drums and straps, for the purpose of working heddle-frames; but I am not aware that an arrangement, whereby the desired movements of the heddle-frames have been effected directly by the rollers and heddle-suspending straps, in the manner shown; that is to say, only the roller or pulley-straps being attached to the treadle-frames, the actuating-straps and rods being attached to treadles outside of the range of the heddle-frames.

The treadles E E E are arranged partly upon one side of the loom, and partly upon the opposite side thereof, as shown in the drawings, and these treadles are connected directly to the ends of the upper rollers D, from which the heddles C are suspended, so that the power required to move the heddles is equally distributed upon both ends of said rollers.

I am aware that a loom has been constructed before my invention, having two sliding cams in the middle of the loom-frame, actuating treadles which were directly attached to the bottom bars of the heddle-frames or harness.

I am also aware that, in very wide looms, two sets of treadles and cams have been placed at considerable distance apart, so that the heddle-frames or harness could be depressed or raised evenly; but, in such cases, the treadles acted directly upon the heddles.

I am also aware that looms have been heretofore constructed, having sliding cams on the outside of the loom-frame, which were attached to the harness by cords and levers, as in Letters Patent No. 66,827.

And, finally, I am aware that looms have been made, having their treadles attached to top rollers, from which the heddles were suspended; but such treadles, and their cams, were arranged in the centres of these looms, and their connecting-wires passed between the heddles, and through the warp, which is a serious objection, remedied by my improvement.

Each set of treadles E, in my improved loom, is arranged between the ends of the heddles and the side of the loom-frame, so that the connecting-wires do not pass through the warp, nor between the heddles, notwithstanding these wires are attached to the top suspension-rollers of the heddles.

This arrangement requires the use of two sliding cams, P P, one for each set of treadles, which cams are applied to grooved hubs, S, and operated so as to receive laterally-sliding movements upon their shaft, F, substantially as described in the Letters Patent numbered 4,645.

The drawings represent the cams, and their hubs, applied upon rectangular portions of the cam-shaft F; but I do not lay claim to this feature as my invention, it having been invented prior to its use by me.

Having described my invention,

What I claim as new, and desire to secure by Letters Patent, is—

1. The combination, with treadles arranged at each side of the loom, of straps and rollers, the straps being connected directly to the rollers from which the heddle-frames are suspended, and by which they are actuated, substantially as described.

2. The combination of laterally-sliding cams P, treadles E E, which are placed at both sides of the loom, and the suspension-rollers D, and straps connected directly to the rollers, substantially as described.

3. Drawing-down drums G, arranged beneath the heddles, and having the latter attached to them, substantially as described, in combination with treadles E E, and straps c' c', arranged outside of the range of the heddle-frames, substantially as and for the purpose described.

4. Straps d, rollers D, heddles C, straps e, and drawing-down rollers G, combined and operating as and for the purpose described.

BARTON H. JENKS.
